Primary Examiner — Daniel J Domino(74) *Attorney, Agent, or Firm* — FisherBroyles, LLP(57) **CLAIM**

The ornamental design for a display device with animated graphical user interface, as shown and described.

DESCRIPTION

This application claims the benefit of U.S. application Ser. No. 16/398,145, filed 29 Apr. 2019, U.S. application Ser. No. 16/398,148, filed Apr. 29, 2019, the disclosure of each of which is incorporated, in its entirety, by this reference.

FIG. 1 is a front view of a display device with animated graphical user interface showing a first image in a sequence; and,

FIG. 2 is a second image thereof.

The appearance of the display device with animated graphical user interface sequentially transitions between the images shown in FIGS. 1-2. The process or period in which an image transitions to another forms no part of the claimed design.

The broken lines shown in FIGS. 1-2 illustrate portions of the display device with animated graphical user interface that form no part of the claimed design.
